CLAIM

The ornamental design for a linear acey-deucy game board, as shown.

DESCRIPTION

FIG. 1 is a front top right isometric view of a linear acey-deucy game board showing my new design;

FIG. 2 is a top view of the linear acey-deucy game board; FIG. 3 is a bottom view of the linear acey-deucy game board;

FIG. 4 is a front view of the linear acey-deucy game board;

FIG. 5 is a rear view of the linear acey-deucy game board;

FIG. 6 is a right side view of the linear acey-deucy game board; and,

FIG. 7 is a left side view of the linear acey-deucy game board.
